UNITED STATES PATENT OFFICE

MELVIN W. PERRY, OF ALGOMA, WISCONSIN

MACHINE FOR GLUING VENEER EDGES

Application filed April 9, 1926. Serial No. 100,842.

This invention relates to machines for gluing the edges of veneer or other thin lumber. In gluing the edges of veneer or other thin lumber of this type, it has been the practice heretofore to hold the strips of veneer together by means of adhesive tape or adhesive strips of paper until the joint dried. The strips had to be removed thereafter, and in addition to this, it was a relatively difficult and slow process.

This invention is designed to overcome the above noted defects, and objects of such invention are to provide a machine for gluing the edges of veneer or other thin sheets of lumber and passing them continuously through the machine and completely drying and hardening the joint prior to discharge from the machine so that when the sheets are discharged from the machine, the joint is dried and finished.

Further objects are to provide a machine which is of very simple construction for accomplishing the above results, and which may be easily used even by an unskilled operator to secure a uniform and reliable joint throughout the entire edge of the veneer sheets, and to provide a machine which may continuously operate to pass one set of sheets of veneer therethrough after another.

An embodiment of the invention is shown in the accompanying drawings, in which:

Figure 1 is a side elevation of the machine.

Figure 2 is a fragmentary plan view thereof.

Figure 3 is a plan view on the line 3-3 of Figure 1.

Figure 4 is an enlarged transverse section on the line 4-4 of Figure 1.

Figure 5 is an enlarged and exaggerated view of an end roller with the corresponding belt pulley in action.

Referring to the drawings, it will be seen that the machine comprises a standard 1 which carries a table 2 upon which the sheets 3 of veneer are placed as indicated in dotted lines in Figure 3. This table is provided with a setting up gauge or thin strip of metal 4 which projects upwardly centrally of the table and forms a stop against which the edges 50 to be glued are pressed. The table is pro-

vided with a recessed portion 5 which carries glue and a very thin disc-like roller 6 is positioned partly in this recess so that it runs in the glue and lifts such glue upwardly and evenly rubs it over the juxtaposed edges of the veneer. A pair of lower rollers 7 are positioned behind the gluing disc 6 and their upper faces are approximately flush with the table top. These rollers cooperate with a similar pair of upper rollers 8 as indicated in Figure 1. The rollers 7 and 8 are set with their axes at an angle so that they draw the sheets towards each other and force their edges tightly together, such edges being previously coated with glue by the disc 6. The lower rollers 7 are carried by the table 2 while the upper rollers 8 are carried by a frame 9 to be hereinafter described in greater detail.

Referring to Figures 1 and 4, it will be seen that a lower heating hollow block 10 and a similar upper block 11 are provided. These heating members may be heated by any suitable means, for example, by means of steam supplied by pipes, such as indicated at 12 and 13 respectively, the steam being led from the heating members by means of pipes 14 and 15, although, of course, the point of entry and exit of the steam may be varied. The heating members may also be heated by other means than steam.

The rear end of the stationary heating member 10 is carried by a standard 16, and the forward end is carried by a bracket 17 bolted to the standard 1 as shown most clearly in Figure 1. The upper member 11 is movable to a slight extent and is provided with yokes or shoes 18 which are carried by rods 19. These rods 19 slidably pass through a supporting bar 20 as shown in Figure 1 and preferably are threaded at their upper ends and provided with nuts 20 to limit the downward motion of the block 11, springs 21 surrounding the rods 19, and force the upper heating member 11 downwardly. The rear end of the upper heating member is provided with a bracket 22, and the forward and rear ends of the lower member 10 are provided with brackets 23 and 24. Between the forward brackets 22 and 24 forward feeding rollers 25 and 26 are positioned, and are driven in

any suitable manner, as by means of the sprocket wheels and chains illustrated. The bracket 23 at the rear of the movable member 10 is similarly provided with a roller 27, and the bracket 9, previously described, is provided with a roller 28, such latter bracket being bolted to the movable heating member 11.

These heating members are smooth on their upper and lower sides and form contacting surfaces for thin metal belts 29 and 30. Preferably, these rollers are flanged, as shown, to suitably guide the belts, and also, it is preferable to provide the belts with small spurs 31 which may be formed by means of rivets whose inner ends are countersunk within the inner lower faces of the belts as illustrated in Figure 5. These belts may be made smooth, if desired.

20 In using the machine the heating members 10 and 11 are heated and transmit their heat to the metal belts which contact with such members throughout the extensive stretches. These belts, therefore, are maintained in a 25 hot condition at all times during the operation of the machine. They are adapted to travel slowly around the heating members.

The operator places a pair of veneer sheets as indicated at 3 in Figure 1 upon the table 2 and slides them into contact with the gauging strip 4. Thereafter, he slides these strips rearwardly across the table and their edges contact with the glue disc 6, and are thus thoroughly coated with glue. These strips 35 pass between the slanting rollers 7 and 8, the roller 7 being preferably driven as indicated. These rollers force the juxtaposed edges tightly together. The strips pass rearwardly between the heated metal belts 29 and 30 and are slowly fed between the heating members 10 and 11. The upper and lower planes of the veneer strips are held in alignment by means of these belts and the glued edges are further dried during their passage between 45 the heating members so that when the strips are discharged from the rear end of the machine they are completely glued and finished. Obviously, the operator immediately places a new pair of sheets of veneer upon the table 50 when the first pair has advanced a sufficient distance, and consequently, the machine operates continuously to glue the successive veneer sheets.

This machine, therefore, avoids all of the 55 delay and inconvenience of the former process, and also insures a uniform and perfect joint.

Further, it is to be seen that the machine 60 may be readily operated even by an unskilled workman, and that the quality of the joint will not vary, but will have uniform characteristics.

It will be seen further that the machine is 65 of very simple construction and is also practical.

Although the invention has been described in considerable detail, such description is intended as illustrative rather than limiting as the invention may be variously embodied and as the scope of such invention is to be determined as claimed.

I claim:

1. A machine of the class described including means for applying glue to opposed edges of veneer sheets, means for bringing said glued edges together, a pair of elongated heating units, metal belts slidably passing between said units and contacting therewith and heated thereby, and adapted to receive the glued edges of the veneer sheets and means for driving said belts.

2. A machine for gluing the edges of veneer sheets comprising a table adapted to receive such sheets, a gluing disc extending upwardly between the veneer strips and adapted to operate upon the juxtaposed edges of the sheets by having opposite flat faces of the disc contacting with the said juxtaposed edges, and continuously traveling heated belts adapted to receive the glued joint and to dry such joint as the belts pass the sheets through the machine.

3. A machine for gluing the edges of veneer sheets comprising a table, a gauging strip against which the edges to be glued may be pressed, a gluing disc in alignment with such strip and adapted to spread glue over said edges, angularly set rollers for forcing the edges into contact with each other, a pair of elongated heating units positioned rearwardly of such table, metal belts slidably passing between such units and contacting therewith and heated thereby, and adapted to receive the glued edges of the veneer sheets, and means for driving such belts.

In testimony that I claim the foregoing I have hereunto set my hand at Algoma, in the county of Kewaunee and State of Wisconsin.
